UNITED STATES PATENT OFFICE.

HUGH RIGG, OF BONNYRIGG, AND ALEXANDER MEIKLEJON, OF DALKEITH,
COUNTY OF MID-LOTHIAN, SCOTLAND.

MACHINE FOR CUTTING COAL OR OTHER MINERALS.

SPECIFICATION forming part of Letters Patent No. 247,950, dated October 4, 1881.

Application filed May 12, 1878. (No model.) Patented in England February 2, 1878.

To all whom it may concern:

Be it known that we, HUGH RIGG and ALEXANDER MEIKLEJON, residing respectively at Bonnyrigg and Dalkeith, in the county of Mid-Lothian, Scotland, and subjects of the Queen of Great Britain and Ireland, have invented certain Improved Mechanism for Cutting Coal or other Minerals, (for which we obtained a patent in Great Britain, No. 437, dated February 2, 1878,) of which the following is a specification.

Our invention consists in the improved device and construction of a machine for cutting coal or other minerals, in which the whole of the working parts are arranged so that the cutting wheel or disk can cut a hole in the mineral to the under side of the sleeper-supporting rails on which the machine travels, thereby leaving no portion of the mineral to be afterward lifted by hand-labor or otherwise. The machine is made so low as to work in very thin and valuable seams, and this in many cases without cutting away any portion of the coal, and with means of adjusting the machine to cut at any angle, at the same time retaining great rigidity and simplicity of construction not hitherto attained. The dragging gear for dragging the machine along the face of the mineral while employed is also improved, so that an endless or fixed chain can be used.

The improved machine is illustrated in the accompanying sheet of drawings, of which Figure 1 is a plan, Fig. 2 a side elevation, and Fig. 3 an end elevation.

The machine comprises a low frame-work, A, constructed of sufficient size and strength to carry the motive-power engines, cutting mechanism, and other parts, and this frame-work is mounted on four wheels, I, running on rails R, to enable the machine to travel along the face of the mineral to be cut or operated on. A strong bracket or gib, H, is fixed to one side of this framing, and carries a rotating disk, F, fitted with cutters G, which, as the machine is fed forward, cut into the face of the coal.

The motive power employed for operating the machine is derived from steam or compressed air acting upon the pistons of two cylinders, B B, mounted on the frame A, the power being transmitted to drive the cutting wheel or disk F through connecting-rods C C fitted to

cranks on a transverse shaft, D, on which there is keyed a bevel-pinion, E, gearing into teeth f on their counterparts, formed on or cut out in the revolving disk F. The cutting-wheel F revolves and cuts into the lower face of the coal while the machine is being slowly fed forward or dragged along the face or wall of the mineral.

The dragging or traveling of the machine along the face of the mineral is accomplished by a chain, P, which is fixed at both ends of the wall of coal or mineral to be cut. The chain P passes round two pitched chain wheels or pulleys, O O', on transverse shafts N N', these pulleys catching the links of the chain, so that when made to rotate they drag the machine along the face of the mineral while it is engaged in cutting. For this purpose the shaft N, carrying the pulley O, is rotated by means of gearing N² from a longitudinal shaft, M, on which there is fixed a worm-wheel driven by a worm, L, on the crank-shaft D.

A clutch, N³, and hand-lever are provided for putting the dragging-pulley O into or out of action.

At each of the corners of the machine are fixed adjustable screws K, bearing onto the axles J of the carrying-wheels I, these screws K being provided and used for raising and lowering the machine to suit the dip and rise of the seam of mineral. This construction of adjusting-screws K and axles J allows of the whole frame-work A, with the disk or cutting wheel F, being adjusted to any angle irrespective of the level of the rails R and sleepers S.

The disk or wheel F may have more or less teeth, to suit the speed considered best for the kind of mineral to be cut. The shape or form of the cutters G, which are bolted to projections F' on the wheel F, may also be varied to suit the nature of the mineral operated on.

The projections F' are faced on both sides alike, so that the cutters G may be bolted on either side and the wheel F driven in the reverse direction. The gib or bracket H, carrying the cutting-wheel F, is fixed to the framing A, so that the wheel F can cut or "hole" to the under side of the supporting-rails R.

We are aware that it is not new to construct a coal-cutting machine with a horizontal rotary

cutter carried by a traveling frame on which is also mounted the driving mechanism, and to adjust the machine to different heights, and to employ the power which drives the cutter 5 to cause the frame to traverse on its rails. These features therefore we do not desire to claim, broadly; but

What we claim as our invention is—

1. The combination of the traveling frame 10 carrying the driving mechanism with the bracket H and cutting-wheel F below the level of the wheels of the frame, as and for the purpose set forth.

2. The combination of the traveling frame, 15 cutting-wheel, and driving mechanism with

crank-shaft, worm L, shafts M and N, and gears, clutch N², wheel O, and chain, all substantially as described.

3. The combination of the traveling frame, cutting-wheel, and driving mechanism with 20 the wheels I, bearings, and adjusting-screws K. In testimony whereof we have signed our names to this specification in the presence of two subscribing witnesses.

HUGH RIGG.
ALEX. MEIKLEJON.
